UNITED STATES PATENT OFFICE

153,036

DESIGN FOR A PLAQUE

William Sabelis, South Gate, Calif.

Application June 6, 1946, Serial No. 130,441

Term of patent 3½ years

(Cl. D29—23)

To all whom it may concern:

Be it known that I, William Sabelis, a citizen of the United States of America, residing at South Gate, in the county of Los Angeles and State of California, have invented a new, original, and ornamental Design for a Plaque, of which the following is a specification, reference being had to the accompanying drawing, forming a part thereof.

In the drawing:

Fig. 1 is a front elevational view of the plaque, embodying my new design.

Fig. 2 is a side elevational view of the same.

Fig. 3 is a rear elevational view of the same.

Fig. 4 is a sectional view of the same on line 4—4 of Figure 1.

I claim:

The ornamental design for a plaque, as shown.

WILLIAM SABELIS.
